W. VON WOLFFRADT.
WINDOW OPERATING MECHANISM,
APPLICATION FILED NOV. 27, 1912.

1,072,893.

Patented Sept. 9, 1913.

UNITED STATES PATENT OFFICE.

WILLIAM VON WOLFFRADT, OF CLEVELAND, OHIO.

WINDOW-OPERATING MECHANISM.

1,072,893.

Specification of Letters Patent.

Patented Sept. 9, 1913.

Application filed November 27, 1912. Serial No. 733,789.

To all whom it may concern:

Be it known that I, WILLIAM VON WOLFFRADT, a citizen of the United States, residing at Cleveland, in the county of Cuyahoga and State of Ohio, have invented a certain new and useful Improvement in Window-Operating Mechanism, of which the following is a full, clear, and exact description.

This invention relates to a window construction and a mechanism for opening and closing the windows.

The construction is more particularly intended for use where the windows are inaccessible, and the object is to provide an effective construction which will accomplish its purpose, employing a minimum number of parts, and further to provide a construction in which the windows may be hinged along one side, preferably along their longest side to the casings, and be permitted a full 90° opening with respect to the cases in which they are mounted.

Generally speaking, the invention comprises the elements and combination thereof set forth in the accompanying claims.

Reference should be had to the accompanying drawings forming a part of this specification, in which—

Figure 1 is an elevation showing the windows and mechanism in position in a wall structure; and Fig. 2 is a central longitudinal section upon Fig. 1.

The casings of the windows are indicated at 1, and the windows, or more particularly the sash, are represented at 2. Obviously the sash may be of any desired construction, and will be hinged to the casings with which they coöperate, preferably along their outer longitudinal sides, these hinges being indicated at 3 in the drawings.

Upon the inside of the casings, that is to say, within the building, there will extend from each sash a diagonal brace indicated at 4. This brace will be secured to the sash upon the side thereof which is opposite to the side of the sash which is hinged to the casing, and will extend rearwardly from the window at an angle which, in the present instance, is shown at substantially 30° .

The brace 4 is maintained in its position by two auxiliary braces represented at 5 and 6. The auxiliary brace 5 extending between substantially the central portion of the hinged side of the sash and the brace 4, while the auxiliary brace 6 is secured to brace 4 and extends to one extremity of the

window,—that is to say, either the top or the bottom of the sash and is there secured. In practice I usually employ a small channel or angle for forming the brace 4.

It will be understood that each of the sashes forming the series of windows which are usually placed together is provided with one of these angularly extending braces 4. At their inner ends these braces are all joined to a rod 7 by a joint which permits articulation of the brace 4 with respect to the rod. In the present instance I have provided adjustable sleeves 8 through which the rod 7 extends, the sleeves being secured upon the rod in proper position, so that the end of each brace 4 will coöperate with a sleeve, the braces 4 being pivotally connected to the aforesaid sleeves which will permit of relative movement.

The rod 7 is moved in any desired manner, and for the purpose I have shown a cable 9 which is secured to the rod at a point indicated at 10. This cable extends over sheaves such as indicated at 11 and 12, and is caused to extend toward the floor of the building to be within easy reach for manipulation.

In placing such windows and mechanism for operating them, as here disclosed, in a building, I would plan to place each successive section of windows such that the windows will open in opposite directions. This will then permit the use of certain sections to the exclusion of others, when the wind is blowing in certain directions where the tendency of the wind would be to open the windows. That is to say, it is more desirable that the wind when strong beat against the exterior of the windows rather than to blow through the open portions, for the reason that the wind thus blowing through the window is very apt to result in inconvenience to the occupants within the building. It will be seen therefore that the ability to open sections of windows in opposite directions is of a decided advantage.

The particular mounting of the sets of windows in the manner herein indicated permits of a full and complete ventilation being obtained without admitting the wind to blow through the building.

Having described my invention, I claim:

1. The combination with a window hinged along one side, a brace secured upon said window upon the side opposite to that which is hinged, said brace extending diagonally

- from the window, an operating rod extending parallel with the window, the said brace having an articulated connection with the rod, said brace receiving the direct thrust 5 and pull in the opening and closing of the window, auxiliary braces extending from points between the ends of the said brace to the window, and means for moving said rod.
- 10 2. The combination with a window hinged along one side, an operating rod extending parallel to the window, a brace secured upon said window upon the side opposite to that which is hinged, said brace extending diagonally and having an articulated connection with the rod, an auxiliary brace secured to said brace between the ends thereof, and extending to the hinge side of the window, and a second auxiliary brace connected with 15 the brace between the ends thereof and extending to and secured at one end of the window, and means for moving said rod.
- 20

3. The combination with a plurality of windows hinged along one side, a movable rod extending parallel with said windows, 25 a brace secured upon each window and extending therefrom at an angle, an auxiliary brace securing the first mentioned brace with the hinged side of the window, and a second auxiliary brace connecting the first 30 mentioned brace with one end of the window, sleeves secured upon the aforesaid rod, said sleeves being hingedly connected with the first mentioned brace, and a flexible cord secured to the said movable rod for operating the same.

In testimony whereof, I hereunto affix my signature in the presence of two witnesses:

WILLIAM VON WOLFFRADT.

Witnesses:
